UNITED STATES PATENT OFFICE.

HERBERT D. GILL, OF KANE, PENNSYLVANIA, ASSIGNOR OF ONE-HALF TO CHARLES J. BRAHLER, OF ERIE, PENNSYLVANIA.

FLUE CLEANER.

1,414,943.

Specification of Letters Patent.

Patented May 2, 1922.

Application filed December 3, 1920. Serial No. 428,063.

To all whom it may concern:

Be it known that HERBERT D. GILL, a citizen of the United States of America, residing at Kane, in the county of McKean 5 and State of Pennsylvania, has invented new and useful Improvements in Flue Cleaners, of which the following is a specification.

The object of the invention is to provide 10 an apparatus for cleaning boiler flues particularly of the fire tube variety wherein the inconvenience incident to the ordinary methods of blowing out the tubes may be avoided and which consist mainly in the fact that the 15 accumulations of dust and soot are blown forward into the fire box to the discomfort and annoyance of as well as injury to the fireman of other attendants, and therefore the particular object in view is to remove 20 such accumulations in such a manner as to discharge the same into the smoke box at the opposite end of the boiler from the fire box and to remove the accumulations successively from the tubes by suction rather than by a 25 blast; and furthermore to provide an apparatus for the purpose indicated which may be readily applied and adapted to boilers of the ordinary construction, and to equip the same with a suction nozzle which may be 30 successively applied to a number of tubes within a comparatively extensive range of operation without removing the discharge nozzle from the tube in which it is located; and with these objects in view the invention 35 consists in a construction and combination of parts of which a preferred embodiment is shown in the accompanying drawings, wherein:—

Figure 1 is a sectional view of the apparatus with the discharge nozzle fitted in a 40 boiler tube.

Figure 2 is an end elevation of the same.

The device consists essentially of a discharge tube 10 having a nozzle 11 adapted to 45 fit into a selected boiler tube indicated at 12, an injector nozzle 13 in communication with a pressure supply pipe 14 adapted to convey fluids such as steam or air under pressure and arranged to discharge axially through 50 the discharge pipe and nozzle, and a suction pipe 15 communicating with the discharge pipe in a position to be affected by the discharge from the injector nozzle 13 to induce a current of air therethrough by suction, 55 said suction pipe terminating in a nozzle 16 adapted for insertion in either of a plurality

of boiler tubes to be cleaned. The discharge and suction nozzles are provided with conical seating nipples 11^a and 16^a respectively, said nipples being detachably fitted respectively upon the discharge and suction pipe ends to provide for interchangeability or substitution of nozzles to correspond with the diameters of the boiler tubes to be cleaned. 60

The supply pipe is fitted with a controlling valve 17 for regulating the discharge from the injector nozzle 13 and in communication with the supply pipe between said valve and the source of pressure supply is a by-pass tube 18 also fitted with a regulating valve 19 and terminating in a clean-out injector nozzle 20 introduced into the casing or coupling 21 which serves to support the injector nozzle 13 and the adjacent extremities of the discharge and suction pipes, in a direction transverse to the axis of the injector nozzle and with its outlet adjacent to that of the injector nozzle and in alignment with the communicating portion of the suction pipe, 75 so that in the event of the suction pipe becoming obstructed or choked by accumulations of soot or dust drawn thereto by the action of the injector nozzle 13, the valve 17 may be closed and the valve 18 opened to project a jet of air or steam under pressure 80 through the nozzle 20 to remove such accumulation and restore the apparatus to an effective working condition. Under normal conditions the by-pass valve 19 is closed to 85 permit the discharge of the fluid under pressure from the injector nozzle to induce a return circulation of air through the suction pipe to the end that the accumulations in the boiler tube in which the suction nozzle 16 is 90 fitted to be drawn through the suction pipe and ejected through the discharge pipe and the boiler tube in which the latter is fitted and thence to the smoke box and stack at the remote end of the boiler. 95

In order to provide for the application of the suction nozzle successively to a plurality of boiler tubes to be cleaned, it is constructed of a looped form having the substantially parallel arms 15^a and 15^b of which the former is terminally attached to the casing or coupling 21 while the latter carries the suction nozzle, the opposite ends of said arms being connected for establishing communication between said arms, and the loop being 105 provided with a plurality of swivel joints of which the joint 24 is axially arranged in a 110

position perpendicular to the joints 22 and 23, so that the free or nozzle bearing end of the suction tube is capable of a swinging movement to the arm 15^a as an axis and also to the 5 arm 15^b as an axis, while the nozzle and the arm 15^b are capable of a swinging movement in a plane parallel with the arm 15^a by reason of the intermediate axially perpendicular joint 24. The swivel joints referred to 10 and illustrated constitute nothing more than loose threaded connections at the points desired. Also obviously the discharge tube 10 which is disposed in axial alignment with the boiler tube in which its terminal nozzle 15 is fitted serves as the axis about which the 15 entire apparatus may be rotated in extending the range of accessibility of the suction nozzle, so that it is possible with one adjustment of the apparatus or with its discharge nozzle 20 seated in a boiler tube, to arrange the suction nozzle in operative relation with any one or all of the boiler tubes within an area having a radius equal to the combined lengths of the arms 15^a and 15^b of the suction pipe. 25 As a further means of obtaining an effective suction in the boiler tube to be cleaned and in which the suction nozzle is fitted, there may be employed a supplemental injector 30 25 fitted in the outer end of the arm 15^a of the suction pipe in position to discharge longitudinally or axially thereof, said nozzle being connected by a flexible tube 26 with a nipple 27 which is in communication with the pressure supply pipe between 35 the controlling valve 17 and the injector nozzle 13, to the end that fluid pressure is connected through said supplemental injector means when the valve 17 is opened to produce a local suction at the outer end of 40 the arm 15^b of the suction pipe. In the construction illustrated the supplemental injector nozzle is suitably fitted in a coupling 28 which receives the end of the arm 15^a of the suction pipe and the adjacent extremity 45 of an elbow 29 by which the arm 15^b is connected therewith.

Moreover it will be seen that in the manipulation of the device the radially disposed arm 15^a of the suction pipe serves as a convenient grip or handhold by which the apparatus may be grasped and maintained in proper relation with the boiler tubes which are under treatment, the freely movable elements of the suction tube being readily moved 50 in one direction or another to fit the terminal nozzle thereof in the several boiler tube ends as the work of cleansing the tubes progresses.

Having described the invention, what is claimed as new and useful is:—

60 1. A flue cleaner having a duality of pipes in intercommunication, means for producing a forced blast in one of the pipes and a suction in the other, said pipes being provided with terminal nozzles for respective 65 engagement with the ends of boiler tubes,

one of said pipes being of looped form and provided with a plurality of swivel joints.

2. A flue cleaner having a duality of pipes in intercommunication, means for producing a forced blast through one of the pipes and a section in the other, said pipes being provided with terminal nozzles for respective engagement with the ends of boiler tubes, one of the pipes being of looped form and provided with a plurality of swivel joints arranged in axially perpendicular 75 relations.

3. A flue cleaner having a duality of pipes in intercommunication, means for producing a forced blast through one of the pipes and a section in the other, said pipes being provided with terminal nozzles for respective engagement with the ends of boiler tubes, one of the pipes being of looped form and having a plurality of axially parallel and 80 axially perpendicular swivel joints.

4. A flue cleaner having a duality of pipes in intercommunication, means for producing a forced blast through one of the pipes and a section in the other, said pipes being provided with terminal nozzles for respective engagement with the ends of boiler tubes, one of the pipes being of looped form and having a plurality of axially parallel 85 swivel joints and an intermediate axially perpendicular swivel joints.

5. A flue cleaner having a blow pipe and a suction pipe in communication therewith, said pipes being in communication with their adjacent ends in angular relation and having 100 their remote ends provided with nozzles for respective engagement with boiler tubes, and an injector nozzle disposed at the junction of said pipes in axial alignment with the blow pipe, the suction pipe having an offset or looped intermediate portion provided with a plurality of swivel joints arranged axially in angular relation.

6. A flue cleaner having intersecting and communicating discharge and suction pipes 110 provided at their free ends with flue engaging nozzles, a valve controlled injector nozzle disposed at the junction of said discharge and suction pipes in axial alignment with the former, and a valved by-pass having 115 an injector nozzle disposed in axial alignment with the adjacent portion of the suction pipe.

7. A flue cleaner having communicating discharge and suction pipes provided at 120 their free ends with flue engaging nozzles, a valve controlled injector nozzle disposed at the junction of said pipes in axial alignment with the discharge pipe, and a supplemental injector nozzle in communication 125 with the suction pipe and disposed in axial alignment with the suction pipe for discharge toward the junction thereof with the discharge pipe.

8. A flue cleaner having communicating 130

discharge and suction pipes provided at their free ends with flue engaging nozzles, a valve controlled injector nozzle disposed at the junction of said pipes in axial alignment with the discharge pipe, and a supplemental injector nozzle in communication with the suction pipe and disposed in axial alignment with the suction pipe for discharge toward the junction thereof with the discharge pipe, said suction pipe being of looped form and having swivel joints arranged in axially parallel and perpendicular relations. 5
